Primary Examiner—Doris Clark
Attorney, Agent, or Firm—Heisler & Associates[57] **CLAIM**

The ornamental design for an enhanced visibility window screen, as shown and described.

DESCRIPTION

FIG. 1 is a front perspective view of the invention in place adjacent a window and with the screen in a stored configuration;

FIG. 2 is a front perspective view of the invention in place adjacent a window and with the screen in a deployed configuration covering an opening in the adjacent window; FIG. 3 is a perspective view of the invention alone; FIG. 4 is a detail of a portion of that which is shown in FIG. 1 with the screen in a stored configuration;

FIG. 5 is a detail of a portion of that which is shown in FIG. 1 with the screen partially deployed; FIG. 6 is a left side view of the invention with mid portions of similar appearance removed, the right side view being a mirror image;

FIG. 7 is a front elevation view of the invention with mid portions of similar appearance removed; FIG. 8 is a right side view of the invention with mid portions of similar appearance removed;

FIG. 9 is a top plan view of the invention; FIG. 10 is a bottom plan view of the invention; FIG. 11 is a rear elevation view of the invention with mid portions of similar appearance removed; and,

FIG. 12 is a right side view of a mid portion of the invention. The broken lines in FIGS. 1-5 and 7-12 are for purposes of illustration only and form no part of the claimed design.
